DOOR OPERATED SIGNAL

Filed July 28, 1930

FIG. 1

FIG. 3

FIG. 2

INVENTOR:

C. Tillberg
H. J. Sanders

ATTORNEY

UNITED STATES PATENT OFFICE

CHARLES TILLBERG, OF CHICAGO, ILLINOIS

DOOR-OPERATED SIGNAL

Application filed July 28, 1930. Serial No. 471,171.

This invention relates to improvements in door operated signals and more particularly to door bells and strikers of that type adapted for use upon doors that are opened and closed frequently, such as the doors of small retail stores, where it is desired to give the attendant, clerk or owner audible notice or warning of the arrival or entrance of a customer or other person. Small retail stores 10 that ordinarily require the attention of but one or two clerks intermittently, the clerk or attendant retiring to the rear of the actual sales room between times, can be advantageously served by audible signals of this nature.

One object is to provide a door bell and striker that is positive and efficient in operation, inexpensive to manufacture, and durable in use. A further object is to provide a door bell and striker that is very easy to install, and that can be applied equally well to doors that open either to the right or left.

With the foregoing and other objects in view the invention consists in the combination and arrangement of parts to be herein-after fully described, pointed out in the claims and illustrated in the accompanying drawing which forms a part of this application for patent and in which—

30 Fig. 1 is a view of the door bell and striker illustrating its application.

Fig. 2 is a view partly in plan and partly in cross section and is taken on the line 2—2 of Fig. 1.

35 Fig. 3 is a cross sectional view taken on the line 3—3 of Fig. 1.

Like reference characters denote corresponding parts throughout.

40 The door bell and striker comprises a bell supported above the door in the path of a striker carried by the door, the striker coming in contact with the bell and ringing the same each time the door is opened or closed 45 and thus giving audible warning to the attendant of the door movement. The striker is made adjustable so that in the more busy periods of the day when the attendant is kept in the store the striker may be manually moved downward with respect to the bell so

that it will not strike the same with the door movements.

The reference numeral 1 denotes a door and 2 that portion of the door casing above the door. To the casing 2 a pair of spaced 55 diametrically opposed angular brackets 3, 4 are secured by rivets or fasteners 5, each bracket being formed with a non-circular perforation 6, said perforations being diametrically opposite each other and connected by 60 the tubular bar 7, the ends thereof being flattened slightly and secured in said perforations 6 as shown quite clearly in Fig. 3.

A pair of opposed twin coil springs 8, 9 encircle said bar 7, said springs being materially larger at their adjacent than at their remote ends which latter ends are made fast to said bar, the larger ends of said springs being spaced apart slightly and extending 70 downwardly into engagement with an angular bell clamp 10 and securely clamped thereto by the metal yoke 11, the free ends 12 of said springs being bent upwardly against the yoke as shown in Fig. 2.

The bell clamp is secured by rivet 13 to the 75 top of the bell 14, said rivet extending into the bell and carrying the hammer 15. The rectangular striker 16 is formed with the longitudinal slots 17, 18 in a common vertical plane, an eye-bolt 19 extending through the 80 slot 17 into the door and a screw 20 extending through the slot 18 into the door so that the striker is capable of manual adjustment vertically upon the door. As the bell 14 is disposed in the path of movement of the 85 striker when the same is in normal raised position, illustrated in Fig. 1, the striker will ring the bell each time the door is opened or closed. The bell is resiliently supported by the springs 8, 9 so that if the door is opened just enough to position the striker inside the bell the subsequent movement of the door will not break the bell as the striker is freed therefrom. When the striker is lowered a certain distance it will not contact with 90 the bell as the door is opened or closed but will move back and forth below the bell.

What is claimed is:—

1. In a door-operated signal, a bell resiliently supported above the door, a slotted 100

striker carried by the door and projecting thereabove for contact, in one position, with said bell, and fasteners disposed in the slotted portions of said striker whereby the same is adjustably secured to the door.

5 2. In a door-operated signal, a bell resiliently supported above the door, a striker for said bell formed with spaced vertical slots disposed in a common plane, and manually operable fasteners disposed in said slots for adjustably securing said striker to the door.

10 3. In a door-operated signal, a striker adjustably secured to the door and projecting thereabove, spaced brackets secured to the door casing above the door, a bar connecting said brackets, springs secured to said bar, and a bell carried by said springs and disposed in the normal path of movement of said 15 striker.

20 4. In a door-operated signal, a striker adjustably secured to the door and projecting thereabove, spaced brackets secured to the door casing above the door, a bar connecting said brackets, opposed spaced coil springs encircling said bar, the remote ends of said 25 springs being directly secured to the bar, the adjacent ends of said springs being relatively large and terminating in downwardly extending portions, and a bell supported directly by said last named spring ends in the 30 normal path of movement of said striker.

35 In testimony that I claim the foregoing as my own I have hereto affixed my signature.

CHARLES TILLBERG.
